UNITED STATES PATENT OFFICE.

HARRY M. TAYLOR, OF CLEVELAND, OHIO.

WASHING-MACHINE.

1,369,495.

Specification of Letters Patent. Patented Feb. 22, 1921.

Application filed October 26, 1920. Serial No. 419,581.

To all whom it may concern:

Be it known that I, HARRY M. TAYLOR, a citizen of the United States, residing at Cleveland, in the county of Cuyahoga and State of Ohio, have invented a new and useful Washing-Machine, of which the following is a specification.

This invention relates to improvements in washing machines, and pertains more especially to improved means for oscillating the tub in which clothes are to be washed and which is contained internally of an upright casing which is open at its upper end.

One object of this invention is to facilitate the oscillation of said tub and to reduce to a minimum the power required for said oscillation.

Another object is to provide improved means for minimizing vibration of tub-oscillating mechanism operated by a water-motor, and to have said motor conveniently located internally of the aforesaid casing and adequately and inexpensively supported from the framework which said casing comprises.

Another object is to have the component members of the tub-oscillating means compactly arranged and to render said means readily accessible for lubrication, simple and durable in construction, reliable in their operation, and not liable to get out of order.

With these objects in view, and to attain any other object hereinafter appearing, this invention consists in certain features of construction, and combinations and relative arrangements of parts, hereinafter described in this specification, pointed out in the claims, and illustrated in the accompanying drawings.

In said drawings, Figure 1 is a top plan of a washing machine embodying my invention. Fig. 2 is a vertical section taken along the line 2—2, Fig. 1, looking inwardly. Figs. 3 and 4 are vertical sections, in detail, taken along the line 3—3 and line 4—4, respectively, Fig. 2, looking in the direction indicated by the arrows. Portions are broken away in the drawings to reduce their size, and Figs. 3 and 4 are drawn on a larger scale than Figs. 1 and 2.

In said drawings is illustrated a washing machine comprising an upright casing which is open at its upper end and (see Figs. 1 and 2) preferably consists of framework 10 and metal plates or sheets 11 covering said framework at the sides. Said casing is

shown mounted on casters 12 applied in any approved manner.

Internally of said casing and surrounded by the framework 10 is a clothes-receiving tub 13 which has a lid or cover 14 applied in any approved manner. Said tub is provided with two substantially horizontal trunnions 15 and 16 which (see Figs. 1 and 3) are arranged at opposite sides respectively of and externally of the tub and in line endwise and supported from the framework 10. Preferably the trunnions 15 and 16 respectively have bearing in journal-boxes 17 and 18 of any approved construction, and the body of the tub 13 is arranged nearer the tub-surrounding framework 10 at its trunnion 16 than at the trunnion 15. The journal-box 18 (see Fig. 3) is rendered rigid with and supported from a member 20 of said framework in any approved manner. The box 17 is supported from said framework through the medium of a substantially horizontal angle-bar which is substantially at a right angle to the trunnion 15 and wholly internally of the casing and arranged with one wing or member 21 thereof projecting downwardly and with its other wing or member 22 projecting in the direction in which said trunnion projects from the body of the tub 13. The member 22 of said angle-bar (see Fig. 2) rests at its ends on and is secured to members 23 of the framework 10. The casing has its side in the direction of which the trunnion 15 and bar-member 22 project spaced far enough from said angle-bar and from said trunnion to permit of the location, between said side of the casing and the tub 13, of my improved tub-oscillating means hereinafter described. The downwardly projecting member 21 of said angle-bar has each end portion thereof terminating, at a point spaced inwardly from the adjacent end of the forwardly projecting wing 22 of the bar, in an arm 25 arranged transversely of said member 22 and projecting toward the last-mentioned side of the casing so as not to interfere with the location of said angle-bar in proximity to the tub 13. Preferably the journal-box 17 is mounted on the member 22 of said angle-bar and secured to said member in any approved manner, and Fig. 3 shows said box flush at its inner end with the inwardly facing side of the wing 21 of said bar. Each trunnion of the tub 13 is shown provided at its inner end with arms 26 which are arranged radially in relation to said

trunnion and secured to and materially reinforce the tub.

The trunnion 15 is one of the component members of my improved tub-oscillating mechanism which also comprises a substantially horizontal downwardly facing reciprocatory rack 27 which is arranged substantially at a right angle to said trunnion and over and spaced from the journal-box 17, 10 and consequently arranged over and spaced from said trunnion. Said tub-oscillating mechanism also comprises a segmental gear 28 arranged under and meshing with the rack 27 and operatively mounted on the 15 trunnion 15.

The rack 27 is operatively connected in any approved manner with a water-motor 30 supported from the framework 10 through the medium of the hereinbefore mentioned 20 angle-bar. The construction and operation of water-motors are too well known to require description and illustration in detail in this specification. Suffice it to state that 25 31 indicates a pipe at which water under pressure is supplied to the motor, and that 32 indicates a pipe at which water is conducted from the motor. The motor 30 is mounted (see Fig. 4) on and secured to the top 33 of a table which has one leg 34 30 mounted on and secured to the member 22 of the aforesaid angle-bar at a point spaced from the journal-box 17 and has another leg 35 which is secured to a member 36 of the adjacent portion of the frame-work 10. The 35 journal-box 17 (see Figs. 1, 2 and 3) is provided at its motor-facing side with an upwardly projecting arm 38 which extends above the rack 27 and is provided with an anti-friction roller 39 which is substantially 40 parallel with the trunnion 15 and arranged over and next said rack and therefore arranged to retain the rack in mesh with the gear 28. The relative arrangement of the parts is such that in the horizontal position 45 of the tub 13, as shown in Fig. 2, the rack 27 and the engaging gear 28 are in their mid position, and obviously therefore said gear and the connected tub are oscillated alternately in opposite directions during the 50 reciprocation of the rack.

Improved means for minimizing the vibration of the component members of the tub-oscillating mechanism during its operation comprise two coiled springs 40 arranged below the wing 22 of the hereinbefore mentioned angle-bar and at opposite sides respectively of the axis of the gear 28. Said springs extend longitudinally of said angle-bar and are connected at their inner 60 ends to said gear and at their outer ends to opposite end portions respectively of said bar. The gear 28 (see Figs. 2 and 3) is provided with a downwardly projecting arm 41 arranged substantially vertically in the 65 mid position of said gear and connected

rack. Arranged at the outer side of the arm 41 is a rigid link-forming member 42 which is substantially parallel with the rack 27 and pivoted centrally between its ends, as at 43, to said arm and has its axis substantially parallel with the axis of the tub 13. Preferably the springs 40 are attached at their outer ends to the arm 25 of opposite end portions respectively of the wing 21 of the aforesaid angle-bar and at their inner ends to opposite ends respectively of the link-forming member 42 and are under tension in the mid position of the rack 27 and engaging gear 28, so that the one or the other spring is placed under greater tension according as the rack and gear are actuated beyond their mid position in the one or the other direction. The connection between each spring 40 and the adjacent arm 25 preferably comprises a hook-bolt to the hook 45 of which is attached said spring, and said arm (see Fig. 4) has a hole 46 at which the shank 47 of said bolt extends loosely through said arm and outwardly beyond the outer side of said arm, and a 90 thumb-nut 48 is threaded at the outer side of said arm onto said shank. Hence, only the nuts 48 on the hook-bolts require manipulation, during or upon the assemblage of the parts, to place the springs 40 under 95 the desired tension in the horizontal and mid position of the tub 13, also, to permit the location and operation of the gear 28 in close proximity to the journal-box 17 the member 22 of the aforesaid angle-bar has a 100 portion thereof bent downwardly, as at 50, along the central portion of the bar to positively avoid interference by said member of said bar with the location and operation of the arm 41 of said gear. 105

What I claim is—

1. In a washing machine, the combination, with a tub having two substantially horizontal trunnions arranged at opposite sides respectively and externally of the tub and in line endwise, means for supporting said trunnions, a substantially horizontal downwardly facing reciprocatory rack arranged over and substantially at a right angle to and spaced from one trunnion, a segmental gear meshing with said rack and operatively mounted on said trunnion, and means for reciprocating the rack, said gear being provided with a downwardly projecting arm, of a substantially horizontal rigid link-forming member which is pivoted centrally between its ends to said arm and substantially parallel with the rack in the horizontal position of the tub, and two springs attached to opposite ends respectively of said link-forming member and somewhat under tension in said position of the tub. 120

2. In a washing machine, an upright casting comprising framework and open at its upper end, a tub arranged internally of said 125

casing and having two trunnions arranged at opposite sides respectively and externally of the tub and in line endwise, a substantially horizontal bar arranged between one of said sides of the tub and the adjacent side of the aforesaid casing and substantially at a right angle to the adjacent trunnion and supported from the aforesaid framework, a journal-box mounted on and secured to said bar and affording bearing to one trunnion, a journal-box affording bearing to the other trunnion and supported from said framework, a substantially horizontal downwardly facing reciprocatory rack arranged over and spaced from the first-mentioned box, a gear meshing with said rack and operatively mounted on the trunnion which has bearing in said first-mentioned box, and rack-reciprocating means above the aforesaid bar.

3. In a washing machine, an upright casing comprising framework and open at its upper end, a tub arranged internally of the casing and having two alined trunnions arranged at opposite sides respectively and externally of the tub, a substantially horizontal bar arranged between one of said sides of the tub and the adjacent side of the casing and substantially at a right angle to the adjacent trunnion and supported at its ends from the aforesaid framework, a journal-box mounted on said bar and affording bearing to one trunnion, a journal-box affording bearing to the other trunnion and supported from said framework, a downwardly facing reciprocatory rack arranged over and spaced from the first-mentioned box and substantially parallel with the aforesaid bar, a segmental gear meshing with the rack and operatively mounted on the trunnion which has bearing in said first-mentioned box, said gear having a downwardly projecting arm, and two coiled springs arranged at opposite sides respectively of the axis of the gear and extending longitudinally of said bar and connected at their outer ends to the bar and at their inner ends to said arm, said springs being under tension in the horizontal position of the tub.

4. In a washing machine, an upright casing which is open at its upper end and comprises framework, a tub arranged internally of said casing and having two alined trunnions arranged at opposite sides respectively and externally of the tub, a substantially horizontal bar arranged between one of said sides of the tub and the adjacent side of the casing and substantially at a right angle to the adjacent trunnion and supported from said framework, a journal-box mounted on said bar and affording bearing to one trunnion, a journal-box affording bearing to the other trunnion and supported from said framework, a downwardly facing reciprocatory rack arranged over and spaced from the first-mentioned box and substantially parallel with said bar, a gear meshing with the rack and operatively mounted on the trunnion which has bearing in said first-mentioned box, and a motor mounted on said bar and operatively connected with the rack.

5. In a washing machine, a tub having two alined external trunnions, framework surrounding the tub, a substantially horizontal bar arranged adjacent and substantially at a right angle to one trunnion and supported from said framework, a journal-box mounted on said bar and affording bearing to said trunnion, a journal-box affording bearing to the other trunnion and supported from the framework, a downwardly facing reciprocatory rack arranged over and spaced from the first-mentioned box and substantially parallel with said bar, a gear meshing with the rack and operatively mounted on the trunnion which has bearing in said first-mentioned box, and a motor arranged laterally of and spaced from said first-mentioned box and operatively connected with the rack, said first-mentioned box being provided at its motor-facing side with an upwardly projecting arm having an anti-friction roller arranged to hold the rack in mesh with the gear.

6. In a washing machine, a tub having two alined external trunnions, framework surrounding the tub, a substantially horizontal angle-bar arranged adjacent and substantially at a right angle to one trunnion and rigid with said framework and disposed with one wing thereof projecting in the direction in which said trunnion projects and with its other wing projecting downwardly and terminating in two arms extending transversely of the under side of the first-mentioned wing and affording bearing to said trunnion, a journal-box mounted on said first-mentioned wing and affording bearing to said trunnion, a journal-box affording bearing to the other trunnion and supported from the framework, a downwardly facing reciprocatory rack arranged over and spaced from the first-mentioned box and substantially parallel with said bar, a segmental gear meshing with the rack and operatively mounted on the trunnion which has bearing in said first-mentioned box and having a downwardly projecting arm, and two coiled springs adjustably connected to the different aforesaid arms respectively of said bar and extending from said arms toward and attached to the arm of the gear.

In testimony whereof, I sign the foregoing specification, this 21st day of October, 1920.

In testimony whereof, I sign the foregoing specification, this 21st day of October, 1920.

HARRY M. TAYLOR.
